UNITED STATES PATENT OFFICE.

FRIEDRICH WIESEHOMEIER, OF RINTELN, GERMANY.

MACHINE FOR THE AUTOMATIC INSERTION OF GLASS BALLS INTO BOTTLE-NECKS.

No. 852,590.

Specification of Letters Patent.

Patented May 7, 1907.

Application filed October 1, 1906. Serial No. 336,935.

To all whom it may concern:

Be it known that I, FRIEDRICH WIESEHOMEIER, a subject of the German Emperor, residing at Rinteln-on-the-Weser, Germany, have invented a Machine for the Automatic Insertion of Glass Balls into Bottle-Necks, of which the following is a specification.

This invention relates to apparatus for the automatic insertion of glass balls into the necks of so-called ball stoppered bottles for containing beverages under pressure such as mineral waters and the like. Hitherto the glass ball had to be placed by hand in the unfinished bottle and owing to the large number of manipulations required a great loss of time was involved which resulted in a considerably decreased output. By the insertion of the glass balls by automatic means a greatly increased efficiency is obtained.

The invention is illustrated in the annexed drawing in which

Figure 1 is a section of the apparatus and Fig. 2 a plan view thereof.

The glass balls *a* in a heated condition are placed in a receptacle *b* provided with a slightly inclined bottom so that the balls tend to roll to one end. To this end a pipe *c* is fitted into which the balls pass one above or after the other. The said pipe is closed by a slide *d* on which rest the balls passing from the receptacle or hopper *b*. A second slide *e* is arranged at a distance below the slide *d* corresponding to the diameter of the ball and on being withdrawn permits a ball to pass through a conduit *f* into the bottle neck.

The operation of the two slides is effected by means of the to-and-fro movement of a sliding rod *g* mounted to run on wheels or rollers *g'*. This movement of the bar is transferred to the slides *d* and *e* by a connecting rod *i* pivoted at *h*. Owing to the fact that the two slides are respectively located above and below said pivotal point *h* both perform movements opposite to each other, that is to say when one slide is withdrawn the second obstructs the passage free through the conduit *f* and vice versa. A third slide *k* is also connected to the connecting rod *i* and supported above the outlet opening of the receptacle *b*. The said slide *k* has a finger *k'* extending downwardly into the receptacle *b* and owing to the shaking or shogging action imparted thereto prevents the balls from joggling so that they pass easily into the pipe *c*.

The movement of the slide rod *g* is pro-

duced by simply placing the bottle thereon and pressing same against an abutment *l* whereupon the released ball rolls through the conduit *f* into the bottle neck. When the ball has arrived at this point the upper end of the bottle that is the bottle head can be completed. The construction of the ball releasing device is of course not confined to the form of construction shown but may be effected by any suitable means provided always that only one ball is released at a time, the other balls remaining in the delivery receptacle. The return movement of the sliding bar *g* into its position of rest takes place either by a spring acting on the connecting rod *m* or by a counter weight or equivalent. The whole apparatus may be made of suitable material and owing to its simple, rapid and efficient action secures an essential increase in the output of bottles.

What I claim as my invention and desire to secure by Letters Patent of the United States is:—

1. Apparatus for the purpose set forth comprising a reciprocatable support for the bottle, a receptacle for the balls, means of communication between said receptacle and the neck of the bottle and means whereby the balls are released one by one from said receptacle into said means of communication.

2. Apparatus for the purpose set forth comprising a reciprocatable support for the bottle, a receptacle for the balls, a conduit in communication with said receptacle and extending therefrom to the neck of the bottle on said support and means operated by said reciprocatable support whereby the balls are released one by one from said receptacle into said conduit.

3. Apparatus for the purpose set forth comprising a reciprocatable support for the bottle, rollers supporting said support, a receptacle for the balls, a conduit in communication with said receptacle and extending therefrom to the neck of the bottle on said support, means operated by said reciprocatable support whereby the balls are released one by one from said receptacle into said conduit and means for agitating the balls in the receptacle aforesaid.

In witness whereof I have signed this specification in the presence of two witnesses.

FRIEDRICH WIESEHOMEIER.
